CONNECTOR FOR BED SECTIONS

Ernest H. Anderson, Jamestown, N. Y.

Application October 15, 1940, Serial No. 361,275

2 Claims. (Cl. 5—287)

This invention relates to improvements in devices for connecting and securing the head and foot sections of beds in upright spaced relationship.

More particularly the invention has to do with the provision of a side rail, on each end of which is located an adjustable fastener that is engageable with the head or foot section of a bed. The fastener may be incorporated in any conventional side or display rail, as desired, and serves therewith to connect and rigidly secure the head and foot sections in desired upright spaced relationship.

One object of the invention lies in the provision of a fastener for rails that may be engaged with conventional members in the head and foot sections of a bed.

Another object of the invention lies in the provision of a fastener and rail adapted to rigidly secure the head and foot sections of a bed in upright spaced relationship.

Another object of the invention lies in the provision of a rail fastener that is adjustable to produce a clamping effect as between the head or foot section and the corresponding rail end.

Another object of the invention lies in the provision of a rail fastener that is extendable beyond the rail end to engage a conventional member of a head or foot section and in turn be retracted to effect pressure abutment of the head or foot section with the corresponding rail end.

Another object of the invention lies in the provision of a rail fastener that may be readily released from engagement with the head or foot section of a bed.

Other and further objects of the invention will be more fully understood from a consideration of the following specification, taken in conjunction with the accompanying drawing; and in which

Figure 1 is a side elevation of the head and foot sections of a bed secured in upright spaced relationship through the use of fasteners embodied in a short rail;

Figure 2 is an enlarged side elevational view of the rail and fasteners as applied to the head and foot sections of a bed, parts being broken away to disclose certain details of the structure;

Figure 3 is a plan view of the rail and fasteners showing the parts in the position of Figure 2;

Figure 4 is a perspective view of a bed rail and fasteners prior to being applied to the head and foot sections of a bed;

Figure 5 is a fragmentary vertical sectional

view of a fastener and rail end illustrating the position of the parts during assembly; and

Figure 6 is a perspective view of one of the fasteners removed from the rail.

Reference is particularly had to the drawing wherein the numerals 10 and 11 are employed to generally designate the head and foot sections, respectively, of a bed. As is common in the manufacture of head and foot sections, each of the four posts 12 is formed with a vertical slot 13, transversely of which a pin 14 is secured. Some side rails are provided with two hook members, and slots 13, therefore, would be of greater length and provided with two pins 14 instead of one. The present invention is so designed as to be engageable with either of the pins in the manner and for the purpose hereinafter described.

For purposes of illustration, the side rail 16 is of the display type, as distinguished from the conventional bed rail. However, it will be understood that the particular length, size, or contour of the rail is of no importance, since the invention is applicable to all types of rails without material alteration.

In the present modification of the invention, the rail 16 is formed from a suitable metal strip and terminates at its ends in right angle flanges 17 that in turn are completed by further flanges 18. An angle plate 19, having flanges 21 and 22, is secured to the body of the rail adjacent flange 17 in any suitable manner, as by welding. Bracket 19 is so positioned that flanges 21 and 22 thereof cooperate with flanges 17 and 18 to form a rectangular compartment 23. It will be noted that the end of flange 18 abuts flange 21 and these parts may be permanently secured, if desired, although it will be apparent from the further description of the invention that this is generally unnecessary. The flange 21 of the bracket may be of larger proportions than flanges 17 or 18 for the purpose of providing a considerable area of abutment with the posts 12 of the head or foot section, and for convenience flange 22 may be formed with converging walls, substantially as shown.

Centrally of each flange 21 is a slot 24 through which a member 26 projects. The outer end of this member is formed with a hook 27, whereas the inner end terminates in a flange 28 through which a suitable aperture 29 is made. A part of the member 26 and the flange 28 is located within the compartment 23. An aperture 31 is made in the flange 17, being substantially in alignment with the aperture 29 of the member 26. A bolt 32 is projected through apertures 29 and 31, the

head 33 being positioned against flange 28, and the threaded end projecting exteriorly of the compartment 23. An expansion spring 34 encircles that portion of the bolt between flange 28 and flange 17. The end of the bolt is fitted with a wing nut 36.

When it is desired to set up the head and foot sections of a bed through the use of the present invention, the rail 16 is moved to project the member 26 into the slot 13 for the purpose of engaging the hook 27 with the pin 14 (see Figure 5). It will be noted that flange 21 of the bracket 19 does not abut the post 12, but as the wing nut 36 is rotated the member 26 is retracted or drawn inwardly of the compartment 23, causing the flange 21 to approach and ultimately abut the adjacent face of the post. The wing nut may be drawn down sufficiently to rigidly secure the rail end to the post. In this position it will be noted the spring 34 is compressed. It frequently occurs, when beds have been assembled for some period of time, that the parts become dirty and the hook cannot readily be disengaged from the pin of the post. Through use of the present invention it is merely necessary to back off the wing nut 36 and the spring 34 is effective to extend the member 26 relative to the bracket 19, thus instantly relieving the abutting pressure of the bracket and post and facilitating ready disengagement of the hook.

Although applicant has shown and described his invention as applied to only one type of rail and head or foot section, it will be understood that his structure is fully applicable to many other types of rails and head and foot sections and that any modification in the structure of the rail fastener for this purpose is contemplated insofar as such modification is within the spirit and scope of the hereunto annexed claims.

Having thus set forth my invention what I claim as new and for which I desire protection by Letters Patent is:

1. In a device for connecting bed sections, a rail, flanges terminating an end of said rail, an

angle plate secured to one of said flanges and the body portion of said rail, said plate cooperating with said rail end flanges to form an enclosure, an adjustable member disposed within 5 said enclosure and having a hook portion projecting through and beyond said angle plate, a bolt joined to said member and having a threaded portion projecting through an opening in one of the rail end flanges, spring means carried by 10 said bolt and being wholly located within said enclosure and normally urging said member into an extended position with respect to said angle plate, and a nut engaged with said bolt and bearing against a flange of said rail and operable to 15 produce a tightening effect to withdraw said member inwardly of said enclosure against tension of said spring means.

2. A device for connecting bed sections in close proximity for display purposes comprising a short rail, laterally offset end flanges forming a part of said rail, angle plates secured in abutment with said end flanges and said rail, said plates serving to abut the bed sections and cooperating with said offset flanges to form enclosures at each end 25 of said rail, adjustable hook members located within said enclosures, said hook members having portions projecting through and beyond said angle plates for engagement with pins carried by said bed sections, bolts joined to said members and having threaded portions projecting through openings in corresponding flanges of the rail ends, spring means carried by said bolts and being wholly located within said enclosures and normally urging said hook members into extended 30 positions with respect to the ends of said rail, nuts engaged with said bolts exteriorly of said enclosures and bearing against corresponding flanges of said rail, said nuts being operable when said hook members are engaged with said sections to draw said hook members inwardly of the enclosure and produce opposed pressure engagement of the bed sections with the ends of 35 said rail.
